UNITED STATES PATENT OFFICE

NATHAN J. SCHLOSS, OF NEW YORK, N. Y.

DESIGN FOR A BLOUSE.

SPECIFICATION forming part of Design No. 12,767, dated February 14, 1882.

Application filed January 13, 1882. Term of patent 3½ years.

To all whom it may concern:

Be it known that I, NATHAN J. SCHLOSS, a citizen of the United States, residing at New York, in the county and State of New York, 5 have produced a new and original Design for a Blouse, of which the following is a specification.

This design consists in a series of parallel plaits on the front of a blouse, said plaits being made to extend from the neck down over about three-fourths of the length of the blouse, and being made to terminate in arrow-head-shaped ornaments. The back of the blouse is ornamented in the same manner.

15 In the accompanying drawings, Figure 1 represents a front view of my blouse. Fig. 2 is a back view of the same.

Similar letters indicate corresponding parts.

In the drawings, the letter A designates a blouse or jacket such as commonly worn by youths of from three to eleven years of age. My blouse is ornamented in front by two rows of plaits, B B, one on each lappet. These plaits may be of the same material and color as that 20 from which the blouse is made, or material of different kind or of different color may be used; and said plaits extend from the collar down to a distance of about three-fourths of the length of the blouse. The bottom ends of 25 the plaits terminate in and are concealed by ornaments C, which have the shape of arrow-heads, and which may be produced in any desired manner—such, for instance, as by embroidery. The back of my blouse is ornamented in a similar manner as the front by 30 two rows of plaits, D D, which extend down from the collar to a distance of about three-

fourths of the length of the blouse, one at each side of the middle seam of the back, and which terminate in ornaments E E.

40 What I claim as new, and desire to secure by Letters Patent, is—

1. The design for a blouse, consisting of two rows of plaits, B B, one on each lappet, said plaits extending down from the collar to a distance of about three-fourths of the length of the blouse, substantially as shown and described.

2. The design for a blouse, consisting of two rows of plaits, B B, one on each lappet, said 45 plaits extending down from the collar to a distance of about three-fourths of the length of the blouse, and terminating in ornaments C, substantially as shown and described.

3. The design for a blouse, consisting of two 50 rows of plaits, D D, one on each side of the middle back seam, said plaits extending down from the collar to a distance of about three-fourths of the length of the blouse, substantially as shown and described.

4. The design for a blouse, consisting of two rows of plaits, D D, one on each side of the middle back seam, said plaits extending down from the collar a distance of about three-fourths of the length of the blouse, and terminating in ornaments E, substantially as 65 shown and described.

In testimony whereof I have hereunto set my hand and seal in the presence of two subscribing witnesses.

NATHAN J. SCHLOSS. [L. S.]
